DESIGN FOR A CIGARETTE HOLDER

Gretyl E. Carson, New York, N. Y.

Application August 12, 1944, Serial No. 114,854

Term of patent 14 years

(Cl. D85—8)

To all whom it may concern:

Be it known that I, Gretyl E. Carson, a citizen of the United States, residing at the city of New York, in the county of New York and State of New York, have invented a new, original, and ornamental Design for a Cigarette Holder, of which the following is a specification, reference being had to the accompanying drawing, forming part thereof.

In the drawing

Fig. 1 is a plan view of a cigarette holder showing my new design, the parts of the holder being shown as assembled together.

Fig. 2 is a similar plan view, showing the parts of the holder as separated.

Fig. 3 is a side elevational view of the assembly of Figure 1.

I claim:

The ornamental design for a cigarette holder, as shown.

GRETYL E. CARSON.
